UNITED STATES PATENT OFFICE.

AXEL W. WAHLIN, OF CHICAGO, ILLINOIS, ASSIGNOR TO GUSTAVE LIDSEEN, OF CHICAGO, ILLINOIS.

PHONOGRAPH-NEEDLE SHARPENER.

1,401,213.

Specification of Letters Patent. Patented Dec. 27, 1921.

Application filed April 30, 1920. Serial No. 377,784.

To all whom it may concern:

Be it known that I, AXEL W. WAHLIN, a citizen of the United States, and a resident of the city of Chicago, in the county of Cook and State of Illinois, have invented 5 certain new and useful Improvements in a Phonograph-Needle Sharpener; and I do hereby declare that the following is a full, clear, and exact description of the same, 10 reference being had to the accompanying drawings, and to the numerals of reference marked thereon, which form a part of this specification.

This invention relates more particularly 15 to an improved type of phonograph needle cutter or sharpener adapted to be placed on the middle portion of a record in playing position and adjustably engaged on the projecting end of the phonograph turntable 20 shaft to permit a fiber needle carried by the phonograph stylus holder to be cut or sharpened without being removed from its holder.

It is an object of this invention to provide a phonograph fiber needle sharpener 25 adapted to cut a fiber needle while it is held in position in the phonograph needle or stylus holder.

It is also an object of the invention to provide a phonograph fiber needle cutter 30 adapted to be adjustably engaged on the projecting end of the phonograph turntable shaft.

A further object of the invention is to provide a fiber needle sharpener wherein 35 a movable cutter having a gear segment formed thereon is adapted to be operated by a lever actuated gear segment to co-act with a stationary cutter to cut off the end of a phonograph fiber needle.

40 It is furthermore an object of this invention to provide a phonograph fiber needle cutter wherein a gear operated cutter is adapted to cut off the end of a needle when held in place by the needle holder of a phonograph reproducer mechanism.

45 It is an important object of this invention to provide a phonograph fiber needle sharpener having a removable chip receptacle adapted to receive the cut off portion 50 of fiber needles which are sharpened by means of gear segment members adapted to actuate a movable cutter when said gear segment members are actuated by depressing a spring-controlled lever.

55 Other and further important objects of

this invention will be apparent from the disclosures in the specification and drawings.

The invention (in a preferred form) is illustrated in the drawings and hereinafter more fully described. 60

On the drawings:

Figure 1 is a top plan view of a phonograph having a needle sharpener of this invention adjustably mounted in position thereon to co-act with a needle held in position by the phonograph reproducer mechanism. 65

Fig. 2 is an enlarged side elevation thereof showing parts in section and parts omitted.

Fig. 3 is a top plan view of a needle sharpener embodying the principles of this invention. 70

Fig. 4 is an end elevation thereof.

Fig. 5 is a sectional view taken on line 75 5-5 of Fig. 3.

Fig. 6 is a sectional view taken on line 6-6 of Fig. 3.

Fig. 7 is a fragmentary detail section taken on line 7-7 of Fig. 3 with parts omitted and showing a needle in position to 80 be cut.

Fig. 8 is a top plan view of the parts shown in Fig. 7 with the needle omitted.

As shown on the drawings:

The reference numeral 1 indicates a phonograph provided with an adjustable sound arm 2, on the end of which is mounted a reproducer mechanism 3. The reproducer mechanism 3 has a stylus or needle holder 4 adapted to hold a wood or fiber needle 5 90 in position. Projecting upwardly through the top board of the phonograph is a rotatable shaft 6, on which is supported a record turntable 7 for supporting a disk record 8 in position to be played. 95

The phonograph needle sharpener or cutter is clearly illustrated in Figs. 3 to 8 inclusive and embraces a base plate 9 provided with an opening 10. Integrally formed at one margin of the base plate 9 100 is a plate extension 11 having a slot 12 therein. Integrally formed on the base plate 9 diagonally opposite the extension 11, is an upright or vertical wall 13 having a curved slot 14 therein. 105

Also integrally formed or rigidly secured to the base plate 9 is a bracket or standard 15, to which one end of a controlling spring 16 is attached. The other end of the spring 16 projects through the curved 110

slot 14 and is secured to an arm or lever 17. One end of the lever 17 is pivotally mounted on the wall 13. A gear segment 18 is integrally formed on the pivoted end of the lever 17, and a knurled finger piece 19 is formed on the outer end of said lever.

Secured by rivets or other suitable means on the base plate 9 is a vertical stationary cutter plate 20 provided with a tapered V-shaped needle notch 21 adapted to receive the playing end of a fiber needle 5. Pivotally mounted on the stationary cutter plate 20, is a rotatable cutter disk 22 cut away to afford a knife edge 23. A gear segment 24 is integrally formed on the rotatable cutter disk 22 and is in mesh with the lever gear segment 18. Secured on the movable cutter disk 22 is a plate 25 provided with a plurality of outwardly projecting prongs 26, 20 adapted to removably hold a cylindrical box or casing 27 in position to receive the cut off ends of the fiber needles. A stop or lug 28 is integrally formed on the plate 25 and projects inwardly toward the stationary cutter plate 20 and affords a means for gaging the amount of material to be cut off of the end of a needle.

The operation is as follows:

The fiber needle sharpener shown in Fig. 3 is adapted primarily to be used to cut or sharpen fiber needles as they are held in position in the needle holder 4 of a phonograph reproducer mechanism 3. The sharpener is placed upon the middle portion of the record 8 so that the upper end of the phonograph turntable shaft 6 projects through the slot 12 of the base plate extension 11. The phonograph tone arm 2 is swung to the center of the record and moved downwardly until the end of the needle 5 engages in the notch 21 of the stationary cutter plate 20.

The sharpener is adapted to be slidably adjusted on the record with the shaft 6 acting as a guide for the sharpener. The sharpener is moved toward the needle 5 until the playing end of the needle contacts the stop 28. To sharpen the needle the lever 17 is depressed against the action of the spring 16. With the depression of the lever the lever gear segment 18 actuates the gear segment 24 and thereby causes the movable cutter disk 22 to rotate. With the rotation of the cutter disk 22 the knife edge 23 is moved 55 to co-act with the stationary cutter 20 to cut off the projecting end of the needle 5 to sharpen the same. The cut off end of the needle falls into the box or casing 27, which when filled may be removed from between the prongs 26 and emptied. Upon release of the lever 17, the spring 16 acts automatically to return the lever 17 to its raised normal position.

It will of course be understood that the sharpener may be placed directly on the

turntable 7 with the shaft 6 projecting upwardly through the slot 12. The sharpener may be adjusted or braced against the shaft 6 to receive and sharpen the playing end of a fiber needle without requiring the needle 70 to be removed from its holder. If desired the sharpener may be used independently of the phonograph. The opening 10 in the base plate 9 affords a means for holding the sharpener in place when the same is to be 75 used.

I am aware that numerous details of construction may be varied through a wide range without departing from the principles of this invention, and I therefore do not 80 purpose limit the patent granted otherwise than necessitated by the prior art.

I claim as my invention:

1. The combination with a phonograph, of a needle sharpener adapted to be adjustably engaged with the phonograph turntable shaft to permit sharpening of the playing end of a needle held in position by the phonograph needle holder.

2. The combination with a phonograph 90 and the reproducer and turntable thereof, of a needle sharpener adjustably engaged on said turntable to permit sharpening of needles held by the reproducer.

3. The combination with a phonograph 95 reproducer, turntable and turntable shaft, of a slotted needle sharpener on said turntable and slidably adjustable on said shaft which projects through the slot of the sharpener, said sharpener adapted to be slidably 100 adjusted with respect to the reproducer to receive the playing end of a needle held by the reproducer to permit sharpening of the needle without removing the same from the reproducer.

4. The combination with a phonograph, of a fiber needle sharpener adapted to be engaged with the projecting end of the phonograph turntable shaft, said sharpener adapted to be slidably adjusted diametrically of said shaft to receive and cut off the playing end of a fiber needle held by the phonograph stylus holder.

5. A phonograph needle sharpener comprising a base, a notched stationary cutter thereon, a movable cutter pivotally mounted on said stationary cutter, a gear segment formed on said movable cutter, a lever pivoted on said base, a gear segment formed on said lever and in mesh with said movable cutter gear segment, a plate secured on said movable cutter, a needle stop formed thereon, prongs integrally formed on said plate, and a casing removably engaged by said prongs for receiving the parts cut off of a 115 needle when sharpened.

6. A phonograph needle sharpener embracing a base, a notched stationary cutter thereon, a movable cutter pivotally mounted on said stationary cutter, a gear segment in- 120 125

tegrally formed thereon, a lever pivotally mounted on said base, a spring for holding the lever in normal operating position, a gear segment integrally formed on said lever and in mesh with the movable cutter gear segment, a plate secured on said movable cutter, a needle stop formed thereon, prongs formed on said plate, and a chip box removably held in place on said plate by

said prongs to receive the cut off parts of 10 needles.

In testimony whereof I have hereunto subscribed my name in the presence of two subscribing witnesses.

AXEL W. WAHLIN.
